UNITED STATES PATENT OFFICE.

HARRY M. WILEY, OF SPOKANE, WASHINGTON.

BURNER.

1,073,830.

Specification of Letters Patent. Patented Sept. 23, 1913.

Application filed April 17, 1913. Serial No. 761,847.

To all whom it may concern:

Be it known that I, HARRY M. WILEY, a citizen of the United States of America, residing at Spokane, in the county of Spokane 5 and State of Washington, have invented certain new and useful Improvements in Burners, of which the following is a specification.

This invention pertains to hydrocarbon-10 burners and has for its object to provide a new and improved burner for use in fire boxes of boilers and other apparatus more especially designed to burn crude oil and arranged to develop a constant flame for producing a high degree of heat in the fire-box 15 or other combustion chamber, and at the same time insuring complete combustion without the production of smoke and obnoxious unburned gases.

Another object of the invention is to produce the greatest possible quantity of heat 20 from the fuel oil.

The invention consists of the novel features and parts and combinations of the 25 same hereinafter fully described and pointed out and embodied in the claims.

In the accompanying drawings forming a part of this specification, Figure 1, is a central, longitudinal sectional view of the 30 burner complete with broken-away views of the connections with a source of oil and of steam supply and a broken-away view of the nozzle taken on the line 1—1 of Fig. 2, and Fig. 2, is a transverse sectional view taken 35 on the line 2—2 of Fig. 1.

Referring now to the detail construction in which like numerals refer to like parts throughout the several views, I have shown a cylindrical oil chamber 10 surrounding a 40 centrally disposed steam passage way 11 extending longitudinally therethrough. At one end of the steam passage way 11 is secured a conduit 12, opening into the passage way 11 and leading to a source of steam supply. At the opposite end of the passage way 45 11 is secured a globular-shaped mixing chamber 13 opening into the passage way 11, and having a nozzle 14 leading therefrom. Opening into the oil chamber 10 is a conduit 50 15 leading to a source of oil supply. Opening from the oil chamber 10 into the steam passage way 11 as at 16 is a valve 17 adapted for manual adjustment. Attached to the end of the valve 17 by means of the 55 stem 18 is a disk 19 occupying a position within the passage way 11.

The wall 20 of the passage way 11 is thickened on one side as at 21 with a gradual increase in thickness extending into the passage way 11 as it approaches the entrance 22 to the mixing chamber 13, such thickness being in a diagonal form as related to the passage way 11, thereby providing a spiral curve to a groove 23 in said thickened portion.

In the practical use of the burner, the same should be arranged horizontally, with the end 14^a of the nozzle 14 extending into the fire box of the furnace, and the part 14^b thereof engaging a passage way through the wall of the furnace leaving the mixing chamber 13 and the remainder of the burner on the outside of the furnace. A supply of oil is turned into the chamber 10 through the conduit 15 and a supply of live, dry steam 75 turned into the passage way 11 through the conduit 12. The heat of the steam passing through the passageway 11 heats the oil in the chamber 10. The valve 17 leading from the chamber 10 into the passage way 11 is 80 opened to supply an adequate amount of oil to be added to the steam in the passage way. The oil after passing through the valve 17 strikes against the disk 19 breaking and atomizing the oil, thereby assisting in the 85 general diffusion of the oil and the steam. The steam coming into the passage way 11 through the conduit 12 on its way to the mixing chamber 13 is given a whirling motion by the deflector 21, causing the mixture 90 of steam and oil to take a winding passage through the mixing chamber 13 in the direction of the arrows, thereby causing a thorough co-mingling of the particles of oil and steam, after which the mixture passes 95 through the nozzle 14 and is burned at a jet at the end 14^a of the nozzle 14. After a great heat has been generated from the action of the steam and the burning at the jet, the mixture of steam and oil is more 100 thorough, vaporizing the lighter constituents of the oil. This gives the maximum amount of heat obtainable from the oil and leaves comparatively no waste in the form of smoke or unconsumed gases.

What I claim is,

1. A hydrocarbon burner comprising a nozzle, a mixing chamber and a passageway, the mixing chamber being between the nozzle and the passageway and opening into each, 110 an oil chamber surrounding the passageway, a conduit opening into the oil chamber lead-

- 2
- ing to a source of oil supply, a conduit opening into the passageway and leading to a source of steam supply and a valve leading from the oil chamber into the passageway,
5 together with a disk suspended into the passageway from the end of the valve and in the path of the oil passing from the oil chamber to the passageway.
2. A hydrocarbon burner comprising a
10 nozzle, a mixing chamber and a passageway, the mixing chamber being between the nozzle and the passageway and opening into each, an oil chamber surrounding the passageway, a conduit opening into the oil chamber leading to a source of oil supply, a
15

conduit opening into the passageway and leading to a source of steam supply and a valve leading from the oil chamber into the passageway, together with an atomizer and a deflector in the passageway adapted to 20 break the particles of oil and co-mingle the same with steam passing through the passageway to the mixing chamber.

In testimony whereof I affix my signature in presence of two witnesses.

HARRY M. WILEY.
